IRONING BOARD

Aaron Wenger, Bayonne, N. J.

Application September 19, 1935, Serial No. 41,247

3 Claims. (Cl. 38—119)

This invention relates to improvements in collapsible ironing boards and particularly to means for mounting and bracing such a board on the supporting legs thereof in a manner affording a greater unobstructed clearance space below the under-surface of the board than has heretofore been possible with other means employed for horizontally supporting such boards.

An important object of my invention is to employ an angular brace member for supporting the board on the legs thereof and mount such a brace member with its apex disposed proximate the hinge between the board and its supporting legs and in which the arms of the brace are disposed respectively in supporting engagement along the under-surface of the board and against the legs thereof.

Another important object of my invention is to provide means for easily and quickly manipulating the brace member into and from board-supporting position. Another object of my invention is to provide supporting means of the class described in combination with an ironing board in which the legs are adapted to collapse upon one another and upon the board itself to dispose the legs in a plane close to and parallel with the board.

Other objects of my invention will either become apparent or be particularly referred to in connection with the description of the illustrative embodiment thereof shown in the accompanying drawing, in which:

Figure 1 illustrates a front elevation of a preferred embodiment of an ironing board employing my invention as the same would appear when the board is opened for use.

Figure 2 is a bottom view of the board and legs shown in Figure 1 and illustrates in dotted lines the position of a rigid angular brace member 40 when it is collapsed against the under-side of the board.

Figure 3 is an end view of the ironing board as seen from the right-hand end of Figure 1.

Figure 4 illustrates a modified form of the angular brace member shown in Figure 1 and the manner in which an articulated angular brace may be employed instead of the rigid brace above described.

Referring to the drawing it will be seen that numeral 10 represents an ironing board having a pair of vertical back legs 11 and a pair of inclined front legs 12 hingeably secured in any suitable manner proximate one end of the board 10, 55 such, for example, as by means of a machine bolt

13 passing through both sets of legs and brackets 14 secured to the under-surface of the board.

The legs 11 and 12, respectively, are secured together as a unit by any suitable means, such as cleats 15 and 16 and cross braces 17 and 18. An 5 articulated brace comprising links 19 and 20 is hingeably disposed between the upper cleats 15 and 16, with the opposite ends of the links hingeably secured, respectively, to said cleats by fixtures 21 and 22. A stop 23 is formed on the link 10 19 to hold it in the position shown when the legs are open for use, it being understood from the drawing that the joint between the links 19 and 20 may be hingeably elevated to permit the legs 11 and 12 to be folded upon one another. 15

My invention is particularly directed to the combination with an ironing board of the class described of an angular or V-shaped brace means 25 having an arm or rigid section 26 extending from a point proximate the hinge 13 along and 20 suitably secured to the under-surface of the board and a second arm or rigid section 27 disposed, when the ironing board structure is open for use, along the inclined legs 12.

An important object of my invention is to employ the stiffening and supporting function of the arms 26 and 27 of an angular brace means of this general type and particularly the supporting effect offered by the ends 28 and 29 thereof; and thereby afford a longer clearance space beneath 30 and between the board 10 and legs 12 than is possible when a straight brace of comparable supporting efficiency is used. 25

In the form of my device shown in Figure 1 the arm 26 is rotatably mounted in bearings 30 and 35 31 secured to the under-side of the board 10. The bearing 30 is provided with a slot 32 through which a screw 33 is inserted and thereafter screwed into the end 28 of the arm 26 to prevent the arm from being withdrawn from the bearing 40 30. A notch 34 formed at the free end of the arm 27 is adapted to engage the upper cleat 16 on the legs 12 when the brace 25 is rotated in the bearings 30—31 and disposed in a plane normal to that of the board, which may be defined as its 45 extended supporting position.

In order to collapse the board 10 and legs 11 and 12, the end 35 of the board is first elevated slightly to disengage the notch 34 and cleat 16, the arm 27 of the brace 25 is then rotated into 50 a plane parallel to that of the board as shown in dotted lines in Figure 2, and the board may then be lowered into parallelism with the legs 12. Thereafter, with the board standing on the ends of legs 12, the brace 19—20 may be manipulated 55

upwardly and the legs 11 lowered into parallelism with the legs 12. In opening the board into a position like that shown in Figure 1, after the legs 11 and 12 are disposed in the position shown, 5 it is only necessary to raise the end 35 of the board 10 because the arm 27 of the brace 25 will, under the force of gravity, swing downward into engagement with the cleat 16.

Referring now to Figure 4, it will be seen that 10 an articulated V-shaped brace having arms or rigid sections 40-41, hinged together at 43 may be employed instead of the rigid brace 25, above described when means is provided for rigidly supporting the free ends of the arms 40-41 in 15 spaced relationship with one another while the device is in extended supporting position. In this form of device the arm 40 is rigidly secured to the bottom of the board 10 in bearings 44 and 45 and the free end of the arm 41 is slidably 20 secured to the cleat 16 by a bearing 46. A strut 47, hinged to the arm 40 at 48 supports the arms in this form of my device when the free end thereof is disposed in a notch 49 formed in the arm 41.

25 In each of the devices shown and described the angular or V-shaped brace means is preferably made of metal of sufficient strength to serve as a stiffening means for the board as well as being a support having an effectiveness at least equal 30 to a straight support disposed between the board 10 and legs 12 at the points of attachment of the bearing 30 and cleat 16 of Figure 1 or the bearings 44-46 of Figure 4. This angular form of support, however, is superior to other forms of 35 support, particularly of the straight bar type, in the matter of affording the clearance beneath the board, above referred to.

40 While I have described what now seems to be the preferred form of a device embodying my invention, various modifications may occur to those skilled in the art in the configuration of the component elements which in combination make up the invention as a whole and no specific limitation is intended by the phraseology 45 of the foregoing description or illustrations in the accompanying drawing.

What is claimed is:

1. An ironing board comprising in combina-

tion, a pair of vertical legs, and a pair of inclined legs secured by hinge means proximate one end of said board, bracing means to hold said legs in supporting position, angular brace means having two rigidly connected, angularly related arms for supporting said board in horizontal position on said legs and bearings secured to the under side of said board for rotatably securing one of said arms thereto, and means for detachably securing the end of the other arm to the inclined legs when the board is disposed in horizontal position.

2. An ironing board comprising in combination, a plurality of supporting legs secured thereto by a single hinge means located proximate one end of said board, bracing means to hold said legs in supporting position, angular brace means for supporting said board in horizontal position on said legs with an unobstructed clearance space below the board from a point proximate said hinge means to the other end of said board, said angular brace means comprising a pair of free-ended angularly related supporting arms one of which is rotatably secured to the under side of said board along the longitudinal axis thereof, and means on the other arm to operatively secure the same to certain of said legs and support the board in horizontal position.

3. An ironing board structure comprising an ironing board member; supporting leg means hingeably secured to the ironing board near one end thereof so that it can assume an extended supporting position and can also fold up close to the board including an inclined leg member; foldable brace means to hold the leg means in extended supporting position including a bar means having rigid sections extending at an angle to each other and a substantial distance from the hinge for the leg means and in which the sections of the bar means are rigid with respect to each other when in board supporting position; means securing one of the sides of the bar means to one of the aforesaid members, the other side of the bar means engaging the other of the aforesaid members whereby said brace means affords a support for the ironing board for a substantial distance from the hinge for said leg means.

AARON WENGER.
